UNITED STATES PATENT OFFICE.

ALBERT J. PITKIN, OF SCHENECTADY, NEW YORK.

COMPOUND ENGINE.

SPECIFICATION forming part of Letters Patent No. 417,083, dated December 10, 1889.

Application filed July 23, 1889. Serial No. 318,418. (No model.)

To all whom it may concern:

Be it known that I, ALBERT J. PITKIN, a citizen of the United States, residing in the city and county of Schenectady, in the State of New York, have made certain new and useful Improvements in Compound Engines, of which the following is a specification.

My invention relates to compound engines of that class in which in starting live steam is simultaneously admitted to both cylinders in order to get the full pressure at starting, in contradistinction to working the steam successively in the high and low pressure cylinders.

15 The objects of my invention are, first, automatically to regulate the admission of live steam to the low-pressure cylinder in starting, and, secondly, automatically to cut off the passage of live steam from the intercepting-valve to the low-pressure cylinder by the action of the exhaust-steam from the high-pressure cylinder upon said intercepting-valve. These ends I attain by interposing between the high and low pressure cylinders an intercepting-valve which automatically opens for the passage of live steam direct to the low-pressure cylinder to start the engine, which valve is subsequently closed by the pressure of the exhaust-steam of the high-pressure cylinder to cut off the direct access of live steam to the low-pressure cylinder, and, when the throttle-valve is closed, remains in this position until live steam is again admitted in starting the engine, when the above-described operations are repeated.

35 The subject-matter is hereinafter specifically designated.

The accompanying drawings show so much of a locomotive-engine embodying my improvements as is necessary to illustrate the subject-matter thereof. Some of these improvements, however, may be used without the others and in machines differing somewhat in their details of construction from those herein shown, and are equally applicable to stationary as to locomotive engines.

Figure 1 is a vertical central longitudinal section through the intercepting-valve and connected parts on the line 1 1 of Fig. 4. Fig. 2 is a vertical transverse section through both cylinders, the intercepting-valve, and connecting mechanism in different planes, the section

through the high-pressure cylinder and its connections being on the line 2 2 of Fig. 3 and that through the low-pressure cylinder 55 and its corresponding parts on the line 2^a 2^a of Fig. 1. Fig. 3 is a vertical longitudinal section through the high-pressure cylinder on the line 3 3 of Fig. 2. Fig. 4 is a plan view showing the low-pressure-cylinder saddle, the 60 reducing-valve, and a part of the intercepting-valve casing. Fig. 5 is a transverse section through the intercepting-valve on the line 5 5 of Fig. 1. Fig. 6 is a similar section through the regulating-valve chamber on the 65 line 6 6 of Fig. 1. Fig. 7 is a plan view of the high-pressure-cylinder saddle. Fig. 8 is a horizontal section through the saddles and intercepting-valve on the line 8 8 of Fig. 2.

Unless otherwise mentioned, the parts are 70 of usual well-known construction.

A smoke-box A is shown in Fig. 2 as connected with saddles B C, in turn respectively connected with the high-pressure cylinder D and low-pressure cylinder E, shown in the 75 drawings as located on opposite sides of the engine, as is common. These cylinders are respectively provided with the usual induction and eduction ports. The exhaust-port d' of the high-pressure cylinder is connected 80 by a pipe or conduit D' with an arch or horseshoe shaped pipe F, which passes around the smoke-box in a well-known way, constituting the usual superheater and receiver, and connects at its other end with the pipe E' and 85 through the intercepting-valve G with the induction-port e of the low-pressure cylinder.

The pipes D, F, and E' constitute a chamber for the reception of exhaust-steam from the high-pressure cylinder before it enters 90 the low-pressure cylinder, and is commonly called a "receiver" or "reservoir."

The drawings show an intercepting-valve G, connected with or forming a part of the saddle C of the low-pressure cylinder. This 95 valve is shown as of a tubular or hollow class, consisting, essentially, of a casing or cylinder g, provided at one end with a detachable head g', secured to the saddle by screws, and at the other with a similarly-secured head g², provided with the usual gland, through which a piston-rod H reciprocates endwise. This rod carries three pistons h h' h², the pistons h' being of the same size, but separated a suf-

ficient distance for the passage of the steam between them when in proper position, they being arranged on the rear end of the piston-rod to operate in connection with the induction-pipe E' of the low-pressure cylinder to allow the steam to pass at the proper time into said cylinder. The remaining piston h^2 is nearer the other or forward end of the valve-cylinder g , and is of smaller diameter than the others, the bore of the cylinder being reduced in that portion traversed by this piston, in order that the other pistons may exert a preponderating pressure on the intercepting-valve at the proper time, as herein-
15 after explained. This part of the cylinder is provided with a live-steam-induction port i , and also with an eduction-port i' , opening direct to the atmosphere for the escape of the steam or condensed water from this portion
20 of the cylinder. The piston h^2 is far enough from the piston h' not to interfere with its proper working, or, in other words, with the admission of steam through it to the interior of the cylinder or bushing g . The central
25 piston h' is provided with ports or openings h^3 , through which live steam may pass to the low-pressure cylinder. Openings or ports j, j' in the cylinder or bushing match with corresponding openings or ports k, k' in the induction-port e of the low-pressure cylinder to admit the passage of the steam through the intercepting-valve.

In order to control, regulate, or time the movements of the intercepting-valve and to prevent its slamming backward and forward, as it would do were the steam turned on without some compensating device, I prolong the piston-rod H through suitable glands in the valve-chamber L , in which a piston l slides.
35 Ports l', l'' connect the opposite ends of this chamber, which is filled with oil or some analogous fluid through an opening l^3 .
40

The area of the passage connecting the parts l', l'' may be varied by a transverse screw l^4 , so as to control the rapidity of the flow of fluid from one side of the piston to the other and the consequent rapidity of the movement of the intercepting-valve.

A lever or link-rod may be attached to the projecting end M of the valve-rod H or the extension thereof, so as to enable the engineer to shift the valve by hand.

A pressure-reducing device or valve S' of well-known construction may be interposed in the live-steam pipe S , leading to the low-pressure cylinder, so as to reduce the pressure therein proportionately to the difference in area of the two pistons. The same result may likewise be obtained by using a pipe of
55 sufficiently small bore to admit only the required amount of live steam to the intercepting-valve and through it to the low-pressure cylinder.

My improved engine operates as follows:
60 The engine stops and normally remains with the valve open for the passage of exhaust-steam from the high to the low pressure cyl-

inder, in which position the intercepting-valve prevents the entrance of live steam through it direct to the low-pressure cylinder. When
70 the throttle-valve is opened, live steam enters the high-pressure cylinder through one branch s of the live-steam pipe S , while live steam simultaneously passes through the other branch s' of this pipe, the pressure-reducing device S' , when one is used, and the intercepting-valve to the low-pressure cylinder, and the engine starts with the full power of both cylinders. The steam from the high-pressure cylinder exhausts
75 into the receiver F , and at the proper time passes through the port k' and opening o and acts on the end of the intercepting-valve. As the area of the pistons h, h' at that end of this valve exceeds that of the front piston h^2 ,
80 the pistons are all forced forward, thus opening the ports j, j', k, k' for the passage of the steam from the receiver or connecting-pipe F into the low-pressure cylinder, at the same time closing the live-steam ports h^3 in the intercepting-valve, and thus cutting off the live steam from direct action upon the low-pressure cylinder, the rapidity of this movement being controlled by the regulating device
85 hereinbefore explained. The intercepting-valve remains in this position as long as the engine is running and when the throttle-valve is closed. When the engine is again started, the live steam forces the intercepting-valve back, so as to close the connection
90 between the receiver F and low-pressure cylinder, while permitting the live steam to flow directly therein, as hereinbefore explained. It will thus be seen that under my improved organization the passage of live
95 steam to the low-pressure cylinder directly through the intercepting-valve is cut off, and live steam is thus prevented from escaping through the communicating-pipe or receiver to the high-pressure cylinder, which would
100 cause back-pressure, and that when the pressure of the exhaust-steam from the high-pressure cylinder in the communicating-pipe or receiver has risen sufficiently it automatically closes the intercepting-valve, and thus
105 cuts off the live steam from direct access to the low-pressure cylinder, simultaneously opening the port for the passage of the steam from the high to the low pressure cylinder, all these motions being automatic.
110

Intercepting-valves in a connecting-pipe between two cylinders have heretofore been constructed in various forms—such, for instance, as a slide-grating through which the exhaust-steam passes from the high to the
115 low pressure cylinder, the valve being actuated in one direction by live steam pressing on a piston in a separate chamber to close the valve and the exhaust-steam from the high-pressure cylinder acting on another piston in a separate closed chamber to open the valve for the passage of the exhaust-steam directly through the grating to the low-pressure cylinder. In such a system, when the
120

valve begins to open, the steam-pressure in its opening chamber becomes reduced so rapidly as to cease acting on the piston before the valve is fully open, and thus not only 5 fails to admit the full head of steam, but to cut off the live steam entirely, and consequently would be practically inoperative. In another form of apparatus an intercepting-valve disk of comparatively large area moves 10 endwise on its spindle to open or close the connection between the two cylinders. When fully open, this valve can be moved in the direction in which it cuts off this connection by live steam acting on its spindle or a small 15 area of its back of the valve; but, as organized, such valve apparently must be opened or closed by hand, or else it would be moved only a short distance in either direction before the pressure of the live and exhaust 20 steam would balance, the valve having both passages open, in which case the live steam would exert back-pressure on the high-pressure piston. In still another form a simple flap-valve is used in the connecting-pipe; but 25 such a device is obviously less desirable than the others, as it has no automatic control over the live-steam port. In my apparatus, on the contrary, the steam from the connecting-pipe or receiver passes transversely through a hole 30 low slide-valve which is moved bodily endwise when the throttle-valve is first opened to close the connection between the cylinders simultaneously with the admission of live steam to the high-pressure cylinder and its 35 passage by another branch pipe to and longitudinally and laterally through other ports to the low-pressure cylinder, the live steam being cut off by the reverse movement bodily of the entire valve, due to the pressure 40 of the steam in the receiver on the opposite end of the valve, which reverse movement also opens the connection between the cylinders.

Having thus fully described the organization 45 and operation of my improved compound engine, what I claim therein as new and of my own invention is—

1. The combination, substantially as hereinbefore set forth, of the high-pressure cylinder, its saddle, the live-steam passage therein, the low-pressure cylinder, its saddle, the intercepting-valve bushing therein, its ports, the live-steam pipe connecting the high-pressure-cylinder passage with the intercepting-valve, the reducing-valve in said pipe, and the

hollow valve movable endwise in one direction in its bushing by the passage of live steam therethrough to the low-pressure cylinder, and in the other by the pressure of the exhaust-steam from the high-pressure cylinder directly on the opposite end of the valve. 60

2. The combination, substantially as hereinbefore set forth, of the branched or forked live-steam pipe, the high-pressure cylinder, the low-pressure cylinder, their connecting-pipe, the low-pressure-cylinder saddle, the intercepting-valve cylinder therein between the steam-pipes and low-pressure cylinder, the three sliding valve-pistons, and the steam-passages through the cylinder and valve for 70 the passage of both live and exhaust steam.

3. The combination, substantially as hereinbefore set forth, of the intercepting-valve bushing or cylinder having steam-ports therein, its two pistons controlling the ports 75 through which the exhaust-steam of the high-pressure cylinder passes, and the live-steam piston of smaller area, and all on the same piston-rod, so as to act in unvarying relation to each other. 80

4. The combination, substantially as hereinbefore set forth, of the intercepting-valve bushing or cylinder having steam-ports therein, the regulator chamber, the pistons of the valve-cylinder and regulator-chamber, and 85 the piston-rod common to all the pistons, so that all move coincidently.

5. The combination, substantially as hereinbefore set forth, of the low-pressure cylinder, its saddle, the connecting-pipe, the hollow slide-valve, its pistons of different areas, 90 and the regulating-chamber.

6. The combination, substantially as hereinbefore set forth, of the intercepting-valve pistons, the regulator-chamber, and the adjusting device to vary the area of its ports to regulate the rate of movement of the intercepting-valve. 95

7. The combination, substantially as hereinbefore set forth, of the intercepting-valve, 100 its pistons, the regulator-chamber, its pistons, and a hand-lever, all connected with the same piston-rod, so as to be able to operate them either automatically or manually.

In testimony whereof I have hereunto subscribed my name.

ALBERT J. PITKIN.
